UNITED STATES PATENT OFFICE.

FREDERICK W. A. BROCKMILLER, OF ST. PETERSBURG, FLORIDA.

ORNAMENTAL FOUNTAIN.

Application filed March 14, 1921. Serial No. 452,225.

To all whom it may concern:

Be it known that I, FREDERICK W. A. BROCKMILLER, a citizen of the United States, residing at St. Petersburg, in the county of Pinellas and State of Florida, have invented certain new and useful Improvements in Ornamental Fountains, of which the following is a specification.

This invention relates to fountains for indoor use, and the primary object of this invention is to provide an improved fountain for use as a soda fountain, or as a window exhibit, which will present a novel and attractive appearance, and which embodies a novel lighting and water display.

Another object of the invention is the provision of an improved fountain embodying a base or tank surrounding a pedestal, a novel means for illuminating the water in the basin, a novel arrangement of transparent or translucent members carried by the pedestal, a novel water display within the ornamental transparent members, means for illuminating said members, and an ornamental illuminated figure arranged above and surrounding the ornamental members.

Another object of the invention is the novel arrangement of the soft drink pipes within the fountain so as to permit the convenient use thereof.

With these and other objects in view, the invention consists in the novel construction, arrangement and formation of parts, as will be hereinafter more specifically described, claimed and illustrated in the accompanying drawings, forming a part of this specification, in which drawings;

Figure 1 is a vertical central section through the improved ornamental fountain.

Figure 2 is a horizontal section taken on the line 2—2 of Figure 1 showing the basin or tank in plan.

Figure 3 is a detail horizontal section through the globe portion of the fountain taken on the line 3—3 of Figure 1, and

Figure 4 is an enlarged fragmentary vertical section through the pedestal portion of the fountain, illustrating the means of mounting the lighting fixtures therein.

Referring to the drawings in detail, wherein similar reference characters designate corresponding parts throughout the several views, the letter A indicates the base of the fountain; B, the pedestal; C, the basin or tank; D, the ornamental globe; F, the ornamental dome; G, the collar or rim for

uniting the globe and dome; H, the ornamental figure for the dome; and I, the illuminating means for the fountain.

The base A is of annular form, and is preferably formed of spun metal, but can be cast if so desired. The base can be provided with ornamental figures if so desired, and includes the outer annular wall 10, the outwardly and downwardly inclined base flange 11, which forms the support. If so desired the flange 11 may be eliminated, and suitable supporting feet substituted therefor. Intermediate the flange 11 and the outer annular wall 10 is the inwardly and horizontally extending flange 12, upon which is seated the lower wall 13. It is desirable that the wall 13 have a water tight connection with the flange 12, so as to prevent the escape of water between the same. The lower wall 13 supports the pedestal or column B, which is disposed at the axial center of the ornamental fountain.

As shown the pedestal or column B includes the hollow tubular column 14 and is preferably made of metal and is provided at its lower end with an outwardly extending flange 15 which forms a shoulder for a purpose which will be hereinafter more fully described. The outer edge of the shoulder or flange 15 supports the depending outwardly extending feet 16, which can be bolted or otherwise secured, as at 17 to the lower wall 13. If desirable the feet 16 can be dispensed with and simply an annular flange substituted in lieu thereof. This flange can be similar to the flange 11 of the base A. A head 18 is provided for the column 14 and can be connected thereto in any preferred manner. As shown the head is connected to the column 14 by means of suitable threads 19. The column 14 and the head 18 can be provided with suitable ornaments if so desired. The head 18 includes the oppositely disposed hollow bowl shaped members 20 and 21, which are connected together by means of a collar 22. If so desired the bowl shaped members 20 and 21 and connecting collar 22 may be formed of separate pieces of metal suitably connected together, or may be cast in a single piece, as shown. The collar 22 extends inwardly of the lower inverted bowl shaped member 20 and supports a relatively large outlet tube 23, the purpose of which also will be hereinafter more fully described.

Extending upwardly through the outlet tube

23 which terminates short of the lower wall 13 is the inlet water pipe 24. The inlet pipe 24 is arranged in spaced relation to the outlet tube 23 and this pipe 24 is provided, 5 intermediate its ends, with a plurality of radially extending branch pipes 25, which extend outwardly through suitable nipples 26 formed on the inverted bowl shaped portion 20 of the head 18. These nipples 26 10 may be of any desired ornamental form, and support the faucets 27, which also may be of ornamental form. The upper end of the water outlet or supply pipe 24 is provided with a rose nozzle 28, which will hereinafter be more fully described.

The tank C surrounds the pedestal B and is supported by the base A and is preferably formed of crystal glass, and includes the 20 inner and outer spaced parallel annular walls 30 and 31 and the connecting lower wall 32. The lower wall 32 rests upon the shoulder or flange 15 and upon a suitable inwardly extending flange 33 carried by the wall 10 of the base A. The outer wall 31 25 has its upper edge provided with a suitable metallic guard flange 34, which also may be of an ornamental character. The inner wall 30 of the tank or basin C terminates short of the upper edge of the outer wall 31, and 30 this inner wall also may be provided with a metallic guard rim or protector 35. If desirable, gold fish or the like may be placed in the tank or basin C. If so desired, the inner wall 30 may be provided with a suitable 35 coating of silver or the like, to form a reflecting surface, and this coating may be protected by a coating of waterproof asphaltum varnish. The lower surface of the bottom wall 32 of the basin C may be provided with a suitable coat of emerald green 40 paint and if desirable this paint may also be waterproofed by a coating of asphaltum varnish.

The globe D is adapted to be supported 45 by the metal bowl portion 21 of the head 18 and this metal bowl portion 21 is provided with an outwardly extending flared rim 40, upon which the globe is adapted to fit. A metallic rim 41 may be provided for the 50 lower edge of the bowl, and this rim is adapted to fit upon the upper surface of the bowl portion 21 of the head 18. The upper edge of the globe D may be also provided 55 with a protecting ring 42 if so desired. It is preferred that the globe D be formed of a transparent material, such as crystal glass, and as shown includes the annular transversely curved wall 43. The dome F is also formed of transparent material, such as 60 crystal glass and includes the annular arcuately curved outer wall 45 and the top concavo-convex wall 46. The lower edge of the wall 45 is provided with an outwardly and downwardly extending flange 47 which 65 forms a shoulder, the purpose of which will

be hereinafter more fully described. The upper edge of the wall 45 is provided with an annular vertically disposed flange 48, which forms a seat for the ornament H. The dome F fits upon the metallic collar or rim G, and as shown this collar or rim G flares outwardly from the upper edge of the globe D and includes the annular transversely curved wall 49, which is provided with the upper outwardly extending flange 50 and the lower depending flange 51, which is extended into the globe D. The inner surface of the wall 49 has secured thereto in any preferred manner, the upwardly extending resilient spring clips 52 which are 70 adapted to engage the shoulder 47 and these clips form means for holding the dome in position.

The ornament H is also preferably formed of transparent or translucent material, and 75 may be of any desired shape or configuration, which is suitable to surmount the dome. While as shown the ornament H is of a spherical formation, it is to be understood that the same may be made to conform to the 80 configuration of a person, and it is desirable that the lower portion of the ornament be frosted, or colored, so as to hide the light which is positioned therein which will be 85 now described. The lower end of the figure, 90 as shown, is provided with an annular wall 53 which fits around the vertical flange 48. A plurality of sprayer pipes 55 are arranged within the globe D and the dome F and are 95 connected in any suitable manner to the rose nozzle 28, and these pipes are adapted to spray the water within the dome F and globe D, and as shown the sprayer pipes 55 are 100 of varying lengths so as to convey the water at various distances within the dome and globe so as to form an ornamental effect.

The illuminating means I for the ornamental fountain includes the lower lighting means 56, the intermediate lighting means 57 and the upper illuminating means 58. 110 The lower illuminating means 56 is carried by the column 14 directly above the water level in the basin or tank C and the column 14 is provided with a plurality of horizontally disposed tubular sleeves 59, which have 115 secured therein the resilient spring clips 60, which are adapted to detachably hold the casing 61 for the illuminating means 56 in position. The casings 61 are of cylindrical 120 form and have mounted thereon the insulating socket 62 for the incandescent bulb 63 and a suitable reflector 64 is mounted within the casing and carries in connection with the casing, an ornamental lens 65, which may 125 have a jewel cut and be of colored glass, such as a ruby or amethyst color. If so desired, the color of the lenses of the illuminating means may be arranged in alternate formation, that is, first a ruby lens and then an amethyst lens. The clips 60 form a novel 130

means for holding the light casings in position. The intermediate lights 57 are provided for illuminating the globe D and are carried by the collar or rim G, which is provided with a plurality of openings, through which the rays from the illuminating means are adapted to shine. This collar or rim G has the inner surface thereof provided with a plurality of resilient clips 66 which support the lamp bases 67 in which incandescent lamps are adapted to be positioned. If so desired, suitable ornamental and colored lenses may be provided for the openings in the collar or rim, directly in front of the incandescent lamps, and also reflectors may be provided for these lamps, similar to the reflectors for the illuminating means 56. The upper illuminating means 58 is arranged within the ornament H and consists of a pair of base plates 70 and 71, which are preferably formed of insulating material, and these plates are held in spaced relation, by means of a spacing ring 72. The lower plate 70 supports a plurality of incandescent lamps 73, which may be of different color, and the upper plate 71 supports a single incandescent lamp 74, which is provided with suitable reflectors 75. A suitable conduit pipe 76 is extended through the lower wall 13 and into the column 14, and this conduit pipe carries suitable electric line wires and protects the same from the water in the pedestal. The wires can be carried from the conduit pipe 76 to the lower intermediate and upper lighting means 56, 57 and 58 respectively, in any preferred manner. It is desirable, however, that the wires be brought up through openings 77 in the inverted bowl portion 20 of the head 18, then brought around the outer surface of the globe D and extended through suitable openings in the collar or rim G and then through suitable openings 78 in the ornament H.

When the device is to be used as a soda fountain, suitable fluid pipes 79 are provided and extended into the base A intermediate the wall 13 thereof and the lower wall 32 of the tank or base C, and these fluid pipes 79 are arranged to extend through the wall 10 of the base and are provided with the ordinary type of soda dispensing faucets 80. The metal utilized in the improved ornamental fountain may be of any kind, such as German silver, brass or copper nickel plated or the like.

In operation of the improved fountain, it can be seen that the water is permitted to flow through the conduit pipe 24, then through the rose nozzle 28 and through the sprayer pipes 55, where the same is thrown outwardly against the sides of the dome and globe F and D. The water will then flow down the sides of the dome and globe through the connecting collar 22 of the

bowl 20 and 21 of the head 18 and then down through the outlet pipe 23 and into the column 14. The water can then flow out of a lower outlet pipe 81 carried by the wall 13, or out of an overflow pipe 82, 70 which is carried by the lower wall 13 of the base A. This pipe 82 defines the water level within the column 14. The water is also permitted to escape into the basin or tank C and it can be seen that the water can 75 be allowed to flow through the faucets 27 and into the base or tank. This also presents a novel and attractive appearance, and the water is made to flow over the upper edge of the inner wall 30 of the tank or basin 80 into the column 14. It can be seen that the lights of different colors of the lower illuminating means 56 will shine directly on the water in the tank C and the water flowing from the nozzles 27, which will give a beautiful effect. The lamps or intermediate illuminating means 57 will also illuminate the globe D and will give a novel and attractive effect, while the upper lighting means 58 will illuminate the ornament H 90 and the dome F.

From the foregoing description, it can be seen that a novel and attractive fountain has been provided of exceptionally simple and durable construction, which can be effectively used either for window display or as a soda fountain.

Changes in details may be made without departing from the spirit or scope of this invention; but,

I claim:

1. A fountain comprising a metallic base, a metallic pedestal carried by the base and arranged at the axial center thereof, an annular basin surrounding the pedestal and supported by the pedestal and base, the basin including an outer annular wall, an inner annular wall, and a connecting lower wall, the inner wall being provided with a reflecting surface, the lower wall being 110 provided with an ornamental surface, transparent members carried by the upper end of the pedestal, an ornamental transparent member surmounting the first mentioned ornamental members, illuminating 115 means disposed in the last mentioned transparent ornamental member, means for spraying water in the first mentioned transparent members, means for illuminating the first mentioned transparent members, means 120 for conveying water from the transparent members through the pedestal to the base, means for spraying water in the basin, and means for draining water from the basin and base.

2. An ornamental fountain comprising a metallic base, an axially disposed metallic pedestal carried by the base, a vitreous basin surrounding the pedestal and supported thereby and by the base, a head car-

ried by the pedestal; a transparent bowl, dome and ornamental figure carried by the head; an outwardly extending flared rim disposed intermediate the globe and dome, 5 a water pipe arranged in the pedestal, and extending into said head, a rose nozzle carried by the upper end of the water pipe, a plurality of spraying pipes of various lengths carried by the nozzle and disposed 10 in the dome and globe, a water outlet pipe carried by the head and arranged in said pedestal and terminating short of the bottom of the base, the water conduit pipe being arranged in the axial center and in 15 spaced relation to the sides of the water exit pipe, rearwardly extending branch pipes connected to the water conduit pipe and arranged exteriorly of the head, spraying nozzles carried by the pipe and disposed 20 above the basin, lower illuminating means carried by the pedestal, intermediate illuminating means carried by the outwardly flared collar or rim, an upper illuminating means disposed in the transparent figure directly 25 above said dome.

3. An ornamental fountain comprising a

base, an axially disposed pedestal carried by the base, a basin surrounding the pedestal and supported thereby and by the base, a head carried by the pedestal; a transparent bowl, dome and ornamental figure carried by the head; a water pipe arranged in the pedestal and extending into said head, a nozzle carried by the upper end of the water pipe, a water outlet pipe carried by the head arranged in said pedestal and terminating short of the bottom of the base, the water conduit pipe arranged in the axial center of the pedestal and in spaced relation to the sides of the water exit pipe, 30 radially extending branch pipes connected to the water conduit pipe and passing through the head to points exterior thereof, bearing nozzles carried by the pipes and disposed above the basin, lower illuminating means carried by the pedestal, intermediate illuminating means disposed intermediate the globe and dome, and upper illuminating means disposed in the transparent figure directly above said dome. 35 40 45 50

FREDERICK W. A. BROCKMILLER
